DESIGN FOR A SERVICE STAND

Hector G. Zoia, Cleveland, Ohio

Application November 26, 1935, Serial No. 59,778

Term of patent 7 years

To all whom it may concern:

Be it known that I, Hector G. Zoia, a citizen of the United States, residing at Cleveland, in the county of Cuyahoga and State of Ohio, have invented a new, original, and ornamental Design for a Service Stand, of which the following is a specification, reference being had to the accompanying drawing, forming part thereof, wherein

Fig. 1 is a side elevation of a service stand showing my new design and Fig. 2 a top plan view of said service stand.

I claim:

The ornamental design for a service stand, substantially as shown.

HECTOR G. ZOIA.
